UNITED STATES PATENT OFFICE

2,145,133

APPARATUS FOR BLENDING LIQUIDS

Arthur H. Riney and Lloyd T. Gibbs, Bartlesville, Okla., assignors to Phillips Petroleum Company, Bartlesville, Okla., a corporation of Delaware

Application September 10, 1935, Serial No. 39,990

3 Claims. (Cl. 277—17)

This invention relates to improved apparatus for blending and dispensing fluids, and in particular relates to new and improved fluid blending devices.

5 The object of this invention is to provide an efficient and accurate device whereby a plurality of fluids may be blended and mixed in any predetermined desired proportion.

10 Another object of this invention is to provide a device for blending and mixing a plurality of fluids whereby the proportions of the liquids constituting the blend can be positively and accurately controlled.

15 While the present invention has a wide range of adaptability and may be used in connection with the blending and mixing of practically any type or kind of fluids, the embodiment of the invention to be herein described has been designed with an especial view to handling liquids of the hydrocarbon type, such as gasoline, fuel oil, and the like.

20 Still further objects and advantages of this invention will be appreciated and become more apparent upon a consideration of the following specification and the attached drawing, forming a part thereof, and wherein like reference characters designate like parts throughout the several views, and wherein.

25 Fig. 1 illustrates diagrammatically one embodiment of the fluid blending and dispensing device.

Fig. 2 is a vertical and sectional view of one form of the fluid blending device.

Fig. 3 is a cross sectional view of the blending device taken on line 3—3 of Fig. 2.

30 In Fig. 1 there is diagrammatically illustrated a system and apparatus for blending and dispensing liquids which consists of a pair of tanks 10 and 10', each constituting a different type of liquid, and which are connected by the pipes 11 and 11' respectively to the inlets 12 and 13 of a blending device or unit 14. The outlet 15 of the blending device discharges the blended liquids into a pipe 16 in which there is interposed a suction pump 17 and a liquid volume flow meter 18. The blending unit 14 is of such a type, as will presently be described, that it is capable of handling a plurality of different liquids and blending them in any desired proportion to produce a single liquid comprising a mixture.

35 In Fig. 1 it will be noted that the pump 17 is interposed in pipe 16 on the discharge side of the blending unit 14, and the full purpose of this will be explained later.

40 One type of blending unit is illustrated in Figs.

2 and 3 and from the later view it will be seen that the same includes a housing or casing composed of a front wall 20 and a rear wall 20'. The rear wall is formed with the two inlets 21 and 22, both of which are screw threaded for connection with pipes. Formed just interiorly of the inlets 21 and 22 in the rear wall 20' there are a pair of vertically arranged elongated slots 23 and 24, which are clearly illustrated in Fig. 2. It should be noted that the slot 24 is considerably longer than the slot 23, and although they both extend to the same height, slot 24 extends downwardly a considerable distance further than slot 23. Between the casing walls 20 and 20' there is positioned a plate 25 having formed therein the rectangular orifices 26 and 27 which are arranged in alignment with inlets 21 and 22 respectively, and which are separated by the web 28. The orifices 26 and 27 are shown in full lines in Fig. 3, and by dotted lines in Fig. 2. The front wall 20' of the casing is so formed as to include an interior chamber 29 connecting with the orifices 26 and 27, and an outlet 30, which is screw threaded to accommodate a pipe.

45 A pair of vertically slidable plates are positioned in the elongated slots 23 and 24. In slot 23 there is positioned the slidable plate 31 which is substantially square in shape, while in slot 24 there is positioned the slidable plate 32 which is substantially rectangular in contour, and has a rectangular aperture or window 33 formed in the top portion thereof which is of a size slightly larger than the orifice 27 formed in plate 25. Due to the construction of the plates 31 and 32 as just explained it will be appreciated that with these plates in the position shown in Figs. 2 and 3, plate 31 is completely closing orifice 26, while orifice 27 is open by virtue of the window 33 in plate 32. The plates 31 and 32 are capable of vertical movement so that the ports 26 and 27 may be opened to any desired degree. Plate 31 is supported upon the lower end of the stem 34, which in turn is suspended from one end of the cross arm 35. Likewise plate 32 is supported by stem 36 which is suspended from the other end of the arm 35. Suitable packings 37 and gland nuts 38 are provided for the stems 34 and 36 at the point where they pass through guideways formed in the blending unit housing or casing.

50 The central portion of the cross arm 35 is provided with a threaded aperture at 39 through which passes the screw threaded stem 40. The stem 40 is provided with an enlarged head 41 which is housed in a recess 42 formed in the top portion of the blending unit casing or hous-

55

ing. Upon the upper end of stem 40 there is secured a hand wheel 43, and below the cross arm 35 and upon the stem 40 there is fixed a nut 44 which serves to restrict the downward movement of the cross arm 35 and thereby also limit the downward movement of the plates 31 and 32. From the above description of the blending unit illustrated in Figs. 2 and 3 it will be appreciated that when the plates 31 and 32 are in the position shown, the orifice 26 will be completely closed, while the orifice 27 will be entirely open. Now by rotating the hand wheel 43 the cross arm 35 will be caused to ride upon the threaded stem 40 and in this manner the stems 34 and 36 will 15 lift or raise the plates 31 and 32. The upward movement of the plate 31 will start to uncover or open orifice 26, while the same movement of plate 32 will begin to close orifice 27. Upon the continued upward movement of these plates the 20 area of the several orifices will vary, with the open area of orifice 26 increasing in direct proportion to the decrease in the open area of orifice 27. This relation will exist until the plates 31 and 32 reach their uppermost limit, at which 25 time orifice 26 will be entirely open and orifice 27 will be completely closed. The several orifices and their respective plates are of such a size and so related that the combined open area of the two orifices at any time and during any position 30 remains a fixed constant, which is equal in area to the area of either of the orifices.

Assuming that a liquid blending device of the type above described is incorporated in the liquid blending system and method of dispensing as 35 illustrated in Fig. 1 and that the same replaces the blending unit 14, one type of liquid from tank 10 would flow through pipe 11 into the inlet 21, and a second type of liquid from tank 10' would flow through pipe 11' into inlet 22. By 40 movement of the hand wheel 43 the plates 31 and 32 may be regulated so as to adjust and control the size of the open area of the orifices 26 and 27 so that the two liquids may be mixed in any desired proportion. Due to the web 28 45 being interposed between the orifices 26 and 27 there is no danger or chance of the liquids leaking from one inlet to the other and so producing inaccuracies in the blend. The two liquids after flowing through the orifices 26 and 27, as regu-

lated and controlled by the plates 31 and 32, then come together as the desired mixture in the chamber 29 from whence they are drawn through the outlet 30 and pipe 16 by the suction pump 17. By positioning the pump 17 on the discharge 5 side of the blending device positive assurance is made that a true mixture and blending of the liquids will take place in strict accordance with the size of the open area of the several orifices. This is true because the suction on both orifices 10 is uniform, and the liquid will flow therethrough in proportion to the size of the open area thereof.

What we claim and desire to secure by Letters Patent is:

1. An apparatus for blending and mixing a 15 plurality of fluids of different characteristics in predetermined proportions, comprising a housing, a mixing chamber therein, inlets in said housing connecting with said chamber, a movable plate having an opening therein for controlling the open area of one of the said inlets and an imperforate movable plate for controlling the open area of another said inlet, the two plates being connected for simultaneous movement in the same direction.

2. An apparatus for blending and mixing a 20 plurality of fluids of different characteristics in predetermined proportions, comprising a housing, a mixing chamber therein, inlets in said housing connecting with said chamber, a movable plate having an opening therein for controlling the open area of one of said inlets and an imperforate movable plate for controlling the open area of another said inlet, the combined 25 open areas in the inlets for any position of the movable plates being equal to the full opening of any one inlet.

3. An apparatus for blending and mixing a 30 plurality of fluids of different characteristics in predetermined proportions, comprising a housing, a mixing chamber therein, inlets in said housing connecting with said chamber, a movable plate having an opening therein for controlling the open area of one of said inlets and an imperforate movable plate for controlling the 35 open area of another said inlet, means for actuating the two plates.
